J. BYSTROM.
LOOSE LEAF BINDER.
APPLICATION FILED DEC. 15, 1919.

1,421,126.

Patented June 27, 1922.

UNITED STATES PATENT OFFICE.

JOHN BYSTROM, OF CHICAGO, ILLINOIS.

LOOSE-LEAF BINDER.

1,421,126.

Specification of Letters Patent. Patented June 27, 1922.

Application filed December 15, 1919. Serial No. 344,822.

To all whom it may concern:

Be it known that I, JOHN BYSTROM, a citizen of the United States, residing at Chicago, in the county of Cook and State of Illinois, have invented certain new and useful Improvements in Loose-Leaf Binders, of which the following is a specification.

This invention relates to improvements in loose leaf binders and one of the objects of 10 the invention is to improve and simplify the construction of devices of this character and at the same time provide an improved device which will be strong and durable in construction and effective and efficient in operation.

A further object is to provide improved means for securing or connecting the various parts together.

A further object is to provide an improved 20 spring construction by means of which the prong carrying members will cause the prongs or rings to be opened and closed with a spring action, and improved means for seating or placing the spring elements in position.

To the attainment of these ends and the accomplishment of other new and useful objects as will appear, the invention consists 30 in the features of novelty in substantially the construction, combination and arrangement of the several parts hereinafter more fully described and claimed and shown in the accompanying drawing illustrating this invention and in which:

35 Figure 1 is a transverse vertical sectional view of an improved device of this character constructed in accordance with the principles of this invention and showing the prongs or ring members closed.

40 Figure 2 is a view similar to Figure 1 showing the prongs or ring members open.

Figure 3 is an enlarged detail sectional view showing the manner of securing one of the prong elements to its supporting plate.

45 Figure 4 is a plan view of one of the elastic spring links.

Figure 5 is a right hand elevation of Figure 4.

Figure 6 is a top plan view of the prong 50 element supporting members showing the prongs in section and showing the operating lever for the members.

Figure 7 is a view partly in section and partly in end elevation.

Figure 8 is a top plan view of the operating lever. 55

Figure 9 is a side elevation of the operating lever showing the manner of connecting it with one of the prong supporting members. 60

Figure 10 is a reduced view of the bottom of the casing.

Figure 11 is a detail reduced perspective view of the back plate.

Referring more particularly to the drawing the numeral 15 designates a base plate of a casing in which the operating parts of the device are located. The casing also embodies a top member 16 and these members are secured together in any suitable manner such as by flanging the edges of the base plate over the edges of the top plate and the casing may be of any desired configuration in cross section. 65

Within the casing thus formed are two 75 substantially flat members 17 which are of a length somewhat shorter than the casing. These members are placed together so that their inner edges 18 will stand in close proximity and these inner edges are provided with ears or lips 19 adapted to overlap the other member to hold the edges of the members against separation. The outer edges of each of these members are provided with any desired number of recesses 20 in which recesses resilient links 21 are adapted to be seated. These links 21 are of a length to encompass the members 17 and when seated in the co-operating recesses 20 will serve to hold the edges 18 of the members 17 together for pivotal action with respect to each other and also serve that when the members 17 are rocked with respect to each other to impart a spring action to the members. 80

The links 21 are shaped so that the ends 22 will overlap and when it is desired to insert or place any of the rings 21 in position intermediate the ends of the members 17, this may be accomplished by turning the ring in such a position that it will lie in substantially the same plane as the plane of the members 17, after which the edge of one of the members 17 is inserted between the overlapping ends 22 of the link and when the link has been passed over the plate, the 105 link may then be twisted at right angles to the member 17 so as to enter recesses 23 as shown in dotted lines in Figure 6. The 100

recesses 23 are preferably spaced a short distance from the adjacent recesses 20 and the edges of the members 17 intermediate the recesses 20—23 are beveled or inclined as at 5 24 so that when the link is seated in the recesses 23 it may be forced into the recess 20 by forcing the link over the inclined portions 24 of the members 17 until the link stands over the recesses 20, at which time 10 the resiliency of the link will cause it to snap into and be seated within the recess 20.

The end links 21 are applied in a similar manner; that is to say the ends of the members 17 are beveled or tapered as at 25 so 15 that the link may be slipped over the ends of the member 17 and then forced over the inclined faces 25 until they spring into the adjacent recesses 20.

Carried by each of the members 17 are 20 prongs or ring elements 26 which may be of any desired size and configuration. One end of each of these elements 26 is provided with a slot or bifurcation 27 to form the walls 28. These elements 26 are secured to 25 the respective members 17 preferably in the following manner. The members 17 are provided in their outer edges with recesses 29 opening through the respective edges, one recess being provided for each of the prong 30 or ring elements 26 to be secured thereto. Adjacent these recesses 29, and spaced therefrom and within the confines of the edges of the member are apertures 30 which are in alinement with the respective recesses 29. 35 To apply the elements 26 the bifurcated portion 27 is passed over the edge of the member 17 so that the element 26 will stand within the recess 29 and will be spaced from the outer edge of the member 17. The extremities of the walls 28 of the slot or bifurcation 27 terminate in alinement with the slot 30 and the extremities of these walls are then bent or deflected towards each other so as to extend partially into the aperture 30 to 40 secure the element 26 in position.

It will thus be seen that with the prongs or ring elements 26 secured to the member 17 that the ends of the elements 26 will abut when the parts are in the position shown in 50 Figure 1, but when the members 17 are rocked with respect to each other, the ends of the elements 26 will be separated or will assume the positions shown in Figure 2.

These members 17 are of a width to fit 55 snugly within the casing formed by the members 15—16 and inasmuch as the prong or ring element 26 is spaced from the edge of the member 17 and inasmuch as a portion of the element 26 will enter the slot 31 in 60 the top 16 of the casing, it will be manifest that the edge of the bottom member 15 may be flanged over the adjacent edge of the member 16 for securing the parts together and the extremity of the flanged edge will 65 terminate short of the element 26 so as not

to interfere with the pivotal movement of the members 17 or the elements 26.

Any suitable means may be provided for rocking the members 17 with respect to each other but preferably a lever indicated generally by the reference numeral 32. This lever is bent so as to form a hook shaped end 33, the extremity 34 of which is preferably inclined and the lever is provided with an operating handle 35. The lever is also 75 provided with laterally projecting arms 36 for holding it in position. This lever 32 is loosely connected with the members 17 through the medium of recesses 37 which open through the inner edges of the members 17 adjacent one end and combine to form a slot into which the end 33 of the lever is hooked. When in position the lever will normally rest upon the bottom member 15 and the arms 36 projecting laterally from the operating lever will engage the wall of the casing to hold the lever in position.

It will thus be seen that assuming the lever to be in the position shown in Figure 9 the elements 26 will be in a locked position 90 with respect to each other, or in a position to hold the leaves in the binder. By depressing the handle 35 the plates 17 will be rocked with respect to each other and the links 21 will impart a spring action to the 95 members 17 so that the co-operating elements 26 will separate with a spring action. In order to cause the elements 26 to assume a locking position with respect to each other the handle 35 of the lever is moved in the 100 opposite direction to move the members 17 about their pivotal edges in the opposite direction, at which time the arms 36 will hold the lever against displacement within the casing and when the members 17 are moved 105 they will travel backwardly with a spring action.

The bottom member 15 of the casing may be provided with any desired number of slots or openings 38 and a flexible member 39 such as cloth or the like is provided for securing this holder in position between covers, etc. The flexible member 39 is secured to the casing member 15 in any suitable manner and a back plate 40 may also be provided 110 which is placed adjacent the outer face of the flexible member 39 where it passes over the member 15. This plate 40 is provided with any suitable number of prongs 41, one for each of the openings 38 so that when the member 40 is placed against the fabric member 39 the prongs 41 will pass through the fabric and enter the respective openings 38 in the casing member 15, after which the extremities of the prongs 41 may be flanged 115 down against the inner face of the casing member 15 for holding the member 40 in position.

While the preferred form of the invention has been herein shown and described, it is to 130

be understood that various changes may be made in the details of construction and in the combination and arrangement of the several parts within the scope of the claims 5 without departing from the spirit of this invention.

What is claimed as new is:—

1. A device of the character described embodying a pair of members pivoted at their 10 inner edges, oppositely disposed and co-operating prongs carried by the respective members, one or more resilient annular links encompassing the members and engaging the outside edges of the members for yieldingly 15 holding the inner edges of said members in pivotal relation, and protecting means for the said links.
2. A device of the character described embodying a pair of members pivoted at their 20 inner edges, oppositely disposed and co-operating prongs carried by the respective members, there being recesses opening through the outer edges of the said members, resilient links encompassing the members and being seated in the said recesses for holding the inner edges of the members in pivotal relation, portions of the said members adjacent the recesses being inclined and over which inclined portions the links are 25 adapted to be forced to enter the recesses.
3. A device of the character described embodying a pair of members pivoted at their 30 inner edges, oppositely disposed and co-operating prongs carried by the respective members, one or more resilient annular links encompassing the members and engaging the outside edges of the members for yieldingly 35 holding the inner edges of said members in pivotal relation, a housing for the said members and links and means connected with the end of said members for imparting pivotal movement of the members one with relation to the other.
4. A device of the character described embodying a pair of members pivoted at their 40 inner edges, oppositely disposed and co-operating prongs carried by the respective members, one or more resilient annular links encompassing the members and engaging the outside edges of the members for yieldingly 45 holding the inner edges of said members in pivotal relation, a housing for the said members and links, there being registering recesses opening through the adjacent edges of 50 the said members to form a slot, and an operating lever engaging in the said slot.
5. A device of the character described embodying a pair of members pivoted at their 55 inner edges, oppositely disposed and co-operating prongs carried by the respective members, one or more resilient annular links encompassing the members and engaging the outside edges of the members for yieldingly 60 holding the inner edges of said members in pivotal relation, a casing enclosing said 65
- members and said links, said members having registering openings through the adjacent edges of the said members to form a slot, an operating lever extending into the casing and engaging in the said slot, and laterally projecting arms on the lever and engaging the casing wall for maintaining the said lever in position.
6. A device of the character described embodying a pair of members pivoted at their 70 inner edges, oppositely disposed and co-operating prongs carried by the respective members, one or more resilient annular links encompassing the members and engaging the outside edges of the members for yieldingly 75 holding the inner edges of said members in pivotal relation, a casing enclosing said member and said links, an operating lever extending into one end of the casing and having a loose connection with the said members for shifting them, and means connected with the lever and co-operating with the said casing wall for maintaining the said lever in position.
7. A device of the character described embodying a substantially flat member having an aperture adjacent but within the confines of one of its edges, a prong element carried by the said member, one end of the prong element being slotted to receive one 80 edge of the said member, the extremity of the slotted end of the prong element terminating in alignment with the aperture in the member, the walls of the slot being deflected towards each other and into the said aperture for securing the prong element to the said member.
8. A device of the character described embodying a substantially flat member having an aperture adjacent but within the confines of one of its edges, a prong element carried by the said member, one end of the prong element being slotted to receive one 85 edge of the said member, the extremity of the slotted end of the prong element terminating in alignment with the aperture in the member, the walls of the slot being deflected towards each other and into the said aperture for securing the prong element to the said member.
9. A device of the character described embodying a casing, prong carrying members within the casing, co-operating prong elements carried by the said members and extending through and beyond the casing, resilient annular members encompassing and bearing upon the outer edges of said members, one wall of the casing having an aperture therethrough, a back plate, a flexible 90
- 100
- 110
- 115
- 120
- 125
- 130

element arranged between the said apertured wall of the casing and the said back plate, and a prong or ear carried by the back plate adapted to penetrate the said flexible element and enter the said aperture in the casing wall, the extremity of the second recited prong or ear being flanged against the inner face of the casing wall.

10. A loose leaf binder embodying a rigid housing, prong-carrying members hinged at their inner edges and disposed within the housing, and resilient annular members also

within the housing, encompassing the first said members and exerting a stress there-upon and from their outer edges, the said prong carrying members being formed for holding said annular members against displacement with respect to the first recited members.

In testimony whereof I have signed my name to this specification, on this 13th day of December, A. D. 1919.

JOHN BYSTROM.
